(57) CLAIM

The ornamental design for a carrying handle for jack, as shown and described.

DESCRIPTION

FIG. 1 is a perspective view of a carrying handle for jack showing our new design;

FIG. 2 is a top view thereof;

FIG. 3 is a bottom view thereof;

FIG. 4 is a rear view thereof;

FIG. 5 is a front view thereof;

FIG. 6 is a first side view thereof; and,

FIG. 7 is a second side view thereof.

The broken lines in the figures are included for the purpose of illustrating portions of the carrying handle for jack which form no part of the claimed design.
